UNITED STATES PATENT OFFICE.

WALTER ALBERT LAPINSKI, OF WAUSAU, WISCONSIN.

CUFF-BUTTON.

1,367,154.

Specification of Letters Patent.

Patented Feb. 1, 1921.

Application filed September 14, 1920. Serial No. 410,111.

To all whom it may concern:

Be it known that I, WALTER A. LAPINSKI, a citizen of the United States, residing at

5 Wausau, in the county of Marathon and State of Wisconsin, have invented certain new and useful Improvements in Cuff-Buttons, of which the following is a specification.

This invention relates to jewelry and 10 more particularly to cuff buttons of the separable type.

The object of the invention is to provide a button of this class the two members of which are separably connected by a clutch.

15 Another object is to provide a button of this character, the parts of which may be quickly connected and cannot be disconnected unless manually released, thereby avoiding all danger of the parts being lost.

20 With these and other objects in view, the invention consists in certain novel features of construction as hereinafter shown and described and then specifically pointed out in the claims, and in the drawings illustrative of the preferred embodiment of the invention.

In the accompanying drawing:

Figure 1 represents a perspective view of 30 a cuff button constructed in accordance with this invention with the parts shown in operative position.

Fig. 2 is a transverse section taken on the line 2-2 of Fig. 1.

Fig. 3 is a vertical section taken on the 35 line 3-3 of Fig. 1, and

Fig. 4 is an enlarged detail sectional view of the clutch.

In the embodiment illustrated the button constituting this invention is composed of 40 two mating members 1 and 10 separably connected by a spring pressed clutch. The member 1 comprises a plate 2 which may be of any desired configuration, but is here shown oblong and has extending at right angles from one face thereof longitudinally spaced plates 3 and 4 of a width slightly less than the width of the plate 2. Projecting laterally outward at right angles from the plates 3 and 4 and parallel with plate 45 2 are two arms 5 and 6 against which are designed to abut when the members are assembled similarly shaped arms 21 and 22 carried by the member 10 as will be hereinafter more fully described.

50 Arranged between plates 3 and 4 and projecting at right angles from plate 2 is

a post 7 designed to be interlockingly engaged with a head 13 carried by the member 10.

The member 10 comprises a plate 11 corresponding in shape and size to plate 2 and carries on its inner face a casing or housing 17 on which is mounted the laterally extending arms 21 and 22 which abut the arms 5 and 6 of member 1 as above described. The outer end of the housing 17 is made solid and has formed on its inner face an outwardly flared seat 19 for a purpose presently to be described.

A tubular member 12 extends through the plate 11 and has a cone shaped head 13 carried by its inner end and which is designed to fit in the seat 19 of the solid portion 18 of the housing 17 as is shown clearly in Fig. 3. This head 13 is provided near 75 its apex with a ball race 14 which communicates with a bore 12^a extending longitudinally through the head and communicating with the interior of tube 12. Mounted in this ball race 14 are a plurality of clutch balls 15 which when the head 13 is forced into seat 19 will grip the pin or post 7 carried by member 1 and lock it in engagement with the member 18.

The outer end of the tubular member 12 85 is provided with a finger grip here shown in the form of a ball 16, but which obviously may be of any other desired configuration, it being designed as an ornament for the cuff button as well as means for releasing 90 the clutch.

Arranged around the tube 12 is a coiled spring 20 which bears at one end against the inner face of the plate 11 and at its other end against the head 13 and operates 95 to normally force said head 13 into the seat 19 and cause the balls 15 to grippingly connect the members 1 and 10.

From the above description it will be obvious that when the parts are connected 100 as shown in Figs. 1 and 3 that they cannot accidentally become separated and can only be released by a pull on the finger grip 16 which moves the head 13 away from seat 19 and disengages the post 7 permitting the 105 members 1 and 10 to be readily separated.

The preferred embodiment of the invention is disclosed in the drawings and set forth in the specification, but it will be understood that any modifications within the 110 scope of the claims may be made in the construction without departing from the

principle of the invention or sacrificing any of its advantages.

What is claimed is:

1. A button of the class described comprising two mating members, one of which is in the form of a plate with spaced plates projecting at right angles from one face thereof and provided with outturned terminal arms and having a post arranged between said plates, the other member having a spring projected ball clutch member for engaging said post to lock it engaged with the first mentioned member.
- 10 2. A button of the class described comprising two mating members, one of which is in the form of a plate with spaced plates projecting at right angles from one face

thereof and provided with outturned terminal arms and having a post arranged between said plates, the other member being in the form of a plate with a laterally extending housing on its inner face adapted to fit between the plates of the first mentioned member, said housing having laterally extending arms to abut the terminal arms of the first mentioned member, and a spring projected cone clutch member arranged within said housing to engage said post and lock the members in operative position.

In testimony whereof I affix my signature hereto.

WALTER ALBERT LAPINSKI.
